JOHN MATTHEWS, JR., OF NEW YORK, N. Y.

Letters Patent No. 84,836, dated December 8, 1868.

IMPROVEMENT IN BOTTLE-FILLING APPARATUS.

The Schedule referred to in these Letters Patent and making part of the same.

To all whom it may concern:

Be it known that I, JOHN MATTHEWS, Jr., of the city, county, and State of New York, have invented a new and useful Improvement in Bottling-Machines, of which the following is a full, clear, and exact description, reference being had to the accompanying drawing, forming part of this specification, and in which—

Figures 1 and 2 represent sectional elevations, at right angles to each other, of a machine or apparatus constructed in accordance with my improvement.

Similar letters of reference indicate corresponding parts.

This, my improvement, is more particularly designed to be applied to apparatus for bottling soda-water, or other liquids under gaseous pressure, and of charging the bottles with sirup or other flavoring-mixtures whilst under the filling-head of the machine; and

This, my invention, consists in a combination of a sirup-pump, or other equivalent device, with the filling-head or corking-plunger, in such manner as that the operation of said head or plunger causes the pump to deposit within the bottle a charge or supply of sirup, or its flavoring-substitute, for admixture with the soda-water or other liquid.

Also, the invention consists in a certain arrangement, with the filling-head or corking-plunger, for automatic operation by said head or plunger, of a sirup-pump or charging-device, made adjustable, to regulate the quantity of sirup or flavoring-mixture discharged by it at each filling-action of the machine.

Referring to the accompanying drawing—

A represents the bottle-table or bed of the machine, with a bottle, shown in red lines, as arranged thereon.

B is the filling-head, which may be of ordinary construction, and is, or may be, carried by a vertically-reciprocating frame, formed, say, of a cross-board, a, fitted to slide up and down guide-rods b, and furnished with bars or rods, c, for connection of it with a treadle, or other suitable operating-contrivance to effect its depression; springs d, wound around the guide-rods b, serving to raise the filling-head, which has connected with it the usual aerated-water nozzle or branch, e, carrying a stop-cock or valve, f, and may further be provided with an ordinary surplus-escape or blow-off branch, similarly provided.

C is the corking-plunger, for reciprocating action or operation, in connection with the filling-head, in or through which it enters or fits in the usual manner, and is, or may be, carried by a secondary or independent frame or board, g, sliding on the guide-rods b, and provided with bars or rods, i, connecting it with a treadle-motion below; or said corking-plunger may be otherwise operated.

Connected with the filling-head B is a sirup-pump, D; or it may be any other appropriate sirup-charging device capable of being opened and closed at intervals by the action of the reciprocating filling-head or cork-

ing-plunger, but preferably the latter, in manner such as that a proper charge or supply of sirup is injected into the bottle as it rests or stands in position for being filled with the aerated water, and prior to the filling up of the bottle with the latter, said pump or sirup-charging device drawing its supply, say, by hose or pipe k, from a sirup-tank above, or otherwise.

The following description of the operation of parts, as arranged in the drawing, will explain how this, my invention, is, or may be, carried into practice.

The bottle being in place, as represented and described, the filling-head is brought down upon it, and the corking-plunger C raised till a projection, m, from it strikes an adjustable nut, n, on a rod, r, which is linked or connected with the plunger s of the pump. This causes a charge of sirup, previously sucked in or admitted by the pump to its barrel, to be injected into the bottle, such admission of sirup to the pump-barrel being effected by the projection m striking a lower adjustable nut, n', which gives to the pump-plunger its downward stroke. The adjustment of the nuts n n' on the rod r serves to regulate the charge, and time of its injection. The upward stroke of the corking-plunger also serves to admit of the insertion of the cork in the filling-head, by the withdrawal of said plunger out of the latter, at its top, after which the corking-plunger is slightly lowered, to hold the cork in the filling-head above the aerated-water branch e, when the cock f is turned, and the aerated water admitted to the bottle, that, being thus filled with the water and charge of sirup, and cock f shut off, is corked by bringing down the plunger C sufficiently low to insure the proper insertion of the cork, and said plunger afterwards temporarily held down while the filling-head is raised, to allow of space for wiring or otherwise fastening the cork.

As before observed, each full descent of the corking-plunger serves, or may serve, to charge the pump with a fresh supply of sirup.

After the bottle has been thus filled, corked, and secured, it is removed, and a fresh bottle introduced to the machine, for a repetition of the process, as described, and which dispenses with any special hand-operation of tap or cock, for charging the bottle with sirup, that is here effected automatically by the general operation of the parts connected with the filling-head or its corking-plunger.

An equivalent automatic action of the sirup-pump or charging-device, by the operation of the filling-head or corking-plunger, may be obtained under a fixed arrangement of the pump, and flexible or other suitable connection of it, with the filling-head, only varying the pump-operating attachments to conform to such change.

I do not claim broadly the combination of a sirup-dispensing or supplying device with a device for supplying soda or mineral-water, as such a combination is described in the patent to A. Quanton, dated March 4, 1856; but

What is here claimed, and desired to be secured by Letters Patent, is—

1. The combination of a sirup-pump or charging-device with the filling-head or corking-plunger of a bottling-machine, in such manner that said pump or charging-device is operated automatically by the filling-head or its corking-plunger, to admit sirup or other flavoring-mixture to the bottle, while the aerated water, or other liquid to be sweetened or flavored, is separately supplied to said bottle as it remains under the filling-head, substantially as specified.

2. The arrangement, essentially as described, of the sirup-pump or charging-device, made adjustable, to regulate its charge, as specified, with the filling-head or corking-plunger, for operation together, substantially as herein set forth.

JOHN MATTHEWS, JR.
